UNITED STATES PATENT OFFICE.

MAURICE LEVISON, OF CHICAGO, ILLINOIS, ASSIGNEE, BY DIRECT AND MESNE ASSIGNMENTS, TO CHICAGO SIGNAL COMPANY, OF CHICAGO, ILLINOIS, A CORPORATION OF ILLINOIS.

ELECTRIC SWITCH.

1,126,494.

Specification of Letters Patent.

Patented Jan. 26, 1915.

Application filed July 17, 1911. Serial No. 638,852.

To all whom it may concern:

Be it known that I, MAURICE LEVISON, a citizen of the United States, residing at Chicago, in the county of Cook and State of Illinois, have invented certain new and useful Improvements in Electric Switches, of which the following is a specification.

My invention relates to improvements in electric switches, and more particularly to 10 signaling call devices for hospital service.

In such signaling systems, it is important that the call initiating apparatus be of a character easily operable by a patient; that it shall operate to set a signal which shall 15 remain in set condition until it is released; and that the release may be effected only through mechanism at the sending station operable by the nurse or attendant whose attendance is demanded by the call.

One of the objects of my invention is to 20 provide an electrical signaling system, wherein the initiation of the call shall set signals at the patient's bed side, and the door of the room, and if necessary, at a remote 25 signal-receiving station; which shall not involve relays in the circuits; and which shall dispense with the cord connections and push button switch usually provided for operation by the patient to initiate the call.

Other objects of my invention are simplicity and economy in the appliances and the coöperative relations thereof, and still further objects of my invention will readily occur to those skilled in the art from the following description taken in conjunction with 35 the accompanying drawings, wherein—

Figure 1 is a perspective view of a signal box; Fig. 2 is a perspective detail of certain of the mechanism in modified form; Fig. 3 40 is a diagram of one circuit; and Fig. 4 is a diagram of a modified circuit.

In general, my invention contemplates the provision at each signal initiating point, say adjacent each patient's bed side, of a 45 combined signal setting and release switch operable by the patient to set a signal (*i. e.*, to cause annunciation of a suitable electrical annunciator) and operable by the nurse to release the signal and prepare the device for 50 operation anew by the patient. Said switching mechanism I arrange in circuit connections including, as annunciators, lamps located at suitable points,—as for instance by

the patient's bed side, at the door of the room, and at the nurse's station,—so that the 55 closing of the switch shall connect all of the annunciators in energized parallel circuits, without the operation of any relay.

Specifically, 10 indicates a box of suitable form; herein shown as a metallic casing, 60 shown as with a clip 11 for attachment to the post of a bed, said casing providing a rear wall, 12, and a peripheral wall 13, having an opening 14 for an operating lever. A closure 15 for the front of the casing is 65 provided, attachable as by screws 16 and having therein a glazed opening 17 for the display of a contained lamp. Within the casing body is provided an insulating base 18, on which all of the current carrying 70 parts are insulated from the box, said base having at its top a shelf 19 on which is mounted a lamp socket 20 to receive a lamp 21. Upon the insulating base are provided a suitable plurality of contacts 22, herein 75 shown as three in number, indicated at 22^a, 22^b, and 22^c, arranged for coöperation with a contact lever 23. I prefer that the switch lever shall be spring-moved in one direction, and manually movable in the other direction 80 to be latched under spring tension, one of its movements being controlled by the patient and the other movement controlled by the nurse.

In the form of construction shown in Fig. 1, 25 indicates a handle applied directly to the lever 23 for moving it downward against the tension of its spring 27, coiled around the pivot 28 for the lever. 30 indicates a latching tooth upon the fulcrum end of the lever 23 arranged for coöperation with a latch 31, pivoted as at 32, and provided with an elevating spring 33 tending to throw the latch to position for engagement with the tooth 30. A pull cord 35 is connected to an insulating block 36 on the latch 31, and is run to a position convenient for operation by the patient. In this construction, when the handle 25 is depressed by a nurse, the contact lever 23 is 100 moved out of contact with the switch contacts 22, and is latched in depressed condition by the latch member 31, spring 27 being put under tension. Accordingly, when the patient pulls the cord 35, withdrawing the 105 latch lever 31 from the tooth 30, the con-

tact 23 springs upward into engagement with the knife switches 22 for circuit closure.

As a more refined construction, somewhat more expensive, but advantageous in many particulars, I may provide in connection with a contact lever 23', a separate operating lever 24, on which the operating handle 25' is mounted, said lever 24 having a finger 24' arranged to extend below the contact lever 23' when both of said levers are depressed, so that the contact lever 23' may be elevated directly with the operating lever 24. A spring 26 is interposed between the two levers 23' and 24 to be put under tension when the lever 24 is depressed in advance of lever 23', and an elevating spring 27' is provided with an operating lever 24, and the latching lever 31 and its equipment are arranged as heretofore described, and latch dog 37 is provided for maintaining the contact lever 23' in raised position, being pressed toward latching position by a spring 38 and arranged to be moved out of operative position by the finger 24' just as the operating lever 24 reaches its most depressed position. In consequence, it will be observed that when both levers 23' and 24 are depressed so that spring 27' is under tension, release of the latch 31 by the nurse frees both levers so that they rise together, throwing the operating lever 23' into association with its contacts 22. In this position, it is latched by the dog 37, so that subsequently, when the nurse depresses the handle 25' of the operating lever, the contact lever 23' remains in raised position for the time being, spring 26 being put under tension owing to the relative depression of the operating lever with respect to the contact lever. Just as the operating lever reaches its lowest position, however, the finger 24' throws the dog 37 out of engagement with contact lever 23', thereby freeing the latter from restraint so that the spring 26 automatically restores the lever 23' to depressed position effecting a quick break action of the switch mechanism. Thus, it is insured that the switches controlled by lever 23' shall remain closed until the operating lever is conditioned for another operation by the patient, and sparking of the contacts is minimized by quick break action so automatically insured.

In Fig. 3 of the drawings, wherein I have diagrammatically illustrated certain circuit connections appropriate to my system, 40 indicates a transformer for stepping down the voltage of an ordinary lighting circuit 41 which may be either a direct or an alternating current. 42 and 43 indicate two main wires run through the area to be supervised, and between which all of the annunciator devices are to be bridged. 21 indicates the bed lamp, 45 indicates the re-

spective door lamp of the room and 46 indicates the pilot lamp, located in the nurse's receiving station. Where one pilot lamp 46 is to be employed for a plurality of rooms or wards, the arrangement may be as indicated in Fig. 3, a wire 48 being run from wire 43 adjacent the source of current supply 40, through the pilot lamp 46, to the several parallel branches 49, each of which is connected to one of the contacts, say 22^b, of each of the switch boxes 10. Bed lamp 21 is connected by wire 50 from the main wire 43 to another contact 22^a for each individual box, and the door lamp 45, common to the ward, has one side connected to the main wire 43, its other side connected by parallel branches 52 to the remaining contact 22^c of the individual boxes 10 which it serves. The contact lever 23 under such circumstances has connection by wire 54 to the remaining main wire 42. It will now be apparent that when one of the switches 23 is closed, parallel circuit paths are established through the several lamps, as follows: Through bed lamp 21 by path 43, 50, 21, 90 22^a, 23, 54, 42; through the appropriate door lamp 45, by path 43, 45, 52, 22^c, 23, 54, 42; and through the common pilot lamp 46, through the path 43, 46, 48, 49, 22^b, 23, 54, 42;—only the bed lamp of the particular patient and the door lamp of the particular ward or room being lighted together with the pilot lamp common to the entire branch of the service.

Where an individual pilot lamp and its third wire 48 is localized to one ward or room, connections may be made as indicated in Fig. 4, the switch members 23 being free from wire connection and wire 54' being connected to one of the contacts, say 22^c, of the switch. As before, the separate wire 48 for each pilot has parallel connection 49 to contacts 22^b of all of the switches of the ward or the single switch of the individual room served by that pilot, and the bed lamp 105 has its individual wire 50 from the wire 43 to the contact 22^a. The door lamp 45 for the ward or individual room may be connected by wire 52' between the third wire or pilot wire 48 and the main wire 43. Under such circumstances, it will be apparent that the closure of the switch of any box 10 will bridge the individual lamp 21 between the main wires 43 and 42 by path 50, 21, 22^a, 23, 22^c, 54'; the pilot lamp by connection 110 48, 46, 49, 22^b, 23, 22^c, 54'; and the door lamp by connection 52', 45, 48, 49, 22^b, 23, 22^c, 54'.

In each instance, it will be observed that all lamps are parallel with each other, so that the incapacitating of any one lamp, as 125 by burning out, does not affect the remaining annunciators which respond to the operation of any switch, or in other words, does no damage beyond elimination of the percentage of lamps injured.

While I have herein described in some detail a particular embodiment of my invention, which I believe to be useful in detail, it will be apparent to those skilled in the art that changes in the details of construction may be made without departure from the spirit of my invention and within the scope of the appended claim.

What I claim is:

- 10 In a switch the combination of a stationary contact, a switch blade adapted to engage the contact, a control lever so positioned that on its extreme movement in one direction it coacts with the blade and presses
- 15 the same into engagement with the contact, a spring resiliently holding the blade and

control lever together, a second spring resiliently holding the control lever in the aforementioned extreme position, a latch for locking the control lever in its opposite extreme position, means for releasing said latch and a second latch for holding the switch blade in contact engaging position, and means carried by the control lever for releasing said last mentioned latch. 20

In testimony whereof I hereunto set my hand in the presence of two witnesses.

MAURICE LEVISON.

In the presence of—

MARY F. ALLEN,
W. LINN ALLEN.
